UNITED STATES PATENT OFFICE.

WILLIAM M. SIMPSON, OF CHICAGO, ILLINOIS, ASSIGNOR TO THE RAILWAY MATERIALS COMPANY, OF CHICAGO, ILLINOIS, A CORPORATION OF ILLINOIS.

BRAKE-SHOE.

1,113,701.

Specification of Letters Patent. Patented Oct. 13, 1914.

Application filed April 28, 1912. Serial No. 693,385.

To all whom it may concern:

Be it known that I, WILLIAM M. SIMPSON, a citizen of the United States, residing at Chicago, in the county of Cook and State of Illinois, have invented certain new and useful Improvements in Brake-Shoes, of which the following is a specification.

This invention relates to railway brake shoes of the general type which comprises a cast metal body reinforced or strengthened by members of wrought-iron, steel or other suitable tough material located at or adjacent to the back of the body and an attaching lug made of tough ductile material anchored to the shoe body, and aims to produce a shoe of this general character in which the wrought-metal attaching lug will be so securely anchored to the shoe body that it can not be detached therefrom even should the shoe body become cracked or fractured.

The invention embodies certain novel features of construction which, together with many of their attendant advantages, will be best understood by referring to the following description when considered in connection with the accompanying drawings illustrating those forms of my invention which at present seem to be preferable.

On the drawings—Figure 1 is a plan view of a shoe in which my invention is incorporated, the shoe body being shown in dotted lines. Fig. 2 is a central longitudinal sectional elevation thereof. Fig. 3 is a transverse sectional view taken on the line 3—3 of Fig. 1. Fig. 4 is a similar view of a slightly modified form of shoe. Fig. 5 is a similar view of another form. Fig. 6 is a transverse sectional view on the line 6—6 of Fig. 1. Fig. 7 is a detail perspective view of one form of attaching lug; and Fig. 8 is a similar view of a modified form of lug.

Referring to the drawings, 10 indicates the body of the brake shoe which is preferably made of cast-iron and may be of any approved shape or configuration. Reinforcing members 11, which in the present instance are shown as relatively narrow plates or bars, are disposed at or adjacent to the back of the shoe body, said members being of any desired contour and having, if preferred, beveled edges 12 as shown in Fig. 1 to enable the body metal to flow up over the edges and firmly unite the members with

the body. Notches or recesses 13 may be provided in the edges of the members to receive the metal of the shoe body for the purpose of forming a more rigid locking engagement between the body and the members. The end lugs 14 and the guide lugs 15 are also formed by the body metal which flows up around the sides and ends of the reinforcing members.

The attaching lug 16 consists of a metal strap or strip bent to the desired shape illustrated in the drawings. This lug, as will be evident from Fig. 2, is of substantially U-shaped form, the ends of the lug being entirely open at the sides of the shoe and the free ends 17 of the strap being bent in opposite directions to extend longitudinally of the shoe. The upstanding portions 18 of the lug are provided with alined openings 19 through which the attaching key is inserted to secure the shoe to the brake head. These openings may be made of the required size and shape to receive the key without running the cast-metal into or around the projecting portion of the lug, this form being shown in Fig. 5. The side walls of the openings in this form are perpendicular to the body of the shoe and parallel with each other. The reinforcing members 11 are inserted through the openings 19 before the shoe is cast and lie flatwise upon the projecting ends 17 of the attaching lug by which they are supported during the casting operation. The members are preferably spaced apart throughout their length to enable the body metal to flow between them and, in order that the projecting ends may be as wide as required, the members are cut away at their central portion as indicated at 20 so that when they are positioned at the ends of the openings 19 their outer edges 90 projecting beyond the lug will lie substantially in alinement with the open sides of the lug.

In the form of lug shown in Fig. 3 the sides of the openings 19 are inclined so that the bottoms of the openings are wider than the tops. This construction permits wider reinforcing members to be employed than would be possible with the straight walled openings shown in Fig. 5. The cast-metal 105 of the shoe body may be run into or around the projecting portion of the lug as shown in Fig. 3 in which the metal fills the open

sides of the lug and reduces the size of the openings 19 to the required M. C. B. dimensions.

The lug shown in Fig. 5 is so constructed that the openings 19 shown therein are of the proper size without running any metal up into and around the lug.

In the shoe shown in Fig. 4 the body metal is not only run inside of the lug but also extends beyond the sides thereof approximately to the sides of the shoe. This metal assists to a certain extent in strengthening the lug but its chief purpose is to reduce the size of the keyway opening to the required dimensions. The metal is preferably run into the lug and across the top as shown in Fig. 2 so that a keyway opening of the exact dimensions required is provided.

20 In the lug shown in Fig. 7 the openings 19 extend from the bent ends 17 to the top of the lug and are cut into the crown flush with the inner faces of the upstanding portions 18. It will be understood that when 25 this type of lug is embodied in a shoe the cast body metal will fill in the upper part of the openings.

In the lug shown in Fig. 8 the openings 19 extend upwardly only to the height of 30 the keyway aperture and the tops of the opening may form the bearing surface for the attaching key, if preferred, without running any of the body metal up into the top of the lug.

35 It will be understood from the foregoing that the size and shape of the openings 19 may be varied considerably and that the cast body metal may or may not be run into or around the attaching lug depending, of course, to a certain extent upon the particular form of lug which is employed. It will be obvious, however, that various changes in the size, shape and proportion of the various parts may be resorted to 45 without departing from the spirit of the in-

vention or sacrificing any of the material advantages thereof.

I claim—

1. A brake shoe comprising an attaching lug formed from a metal strap bent into substantially U-shape with the extremities thereof projecting longitudinally of the shoe, said lug being provided with alined keyway apertures, a plurality of reinforcing members disposed in said apertures and resting upon said longitudinally projecting extremities of the lug, said members being narrower at the center than at the ends so that the outer edges thereof will lie substantially in alinement with the ends of said lug, and a body cast on said members.

2. A brake shoe comprising an attaching lug formed from a metal strap bent into substantially U-shape with the extremities thereof extending outwardly in opposite directions, said lug being provided with alined keyway apertures, a plurality of reinforcing members projecting through said apertures and engaged with said outwardly projecting extremities, the ends of the lug 70 being disposed substantially in alinement with the sides of the reinforcing members, and a body cast on said members.

3. A brake shoe comprising an attaching lug formed from a metal strap bent into substantially U-shape with the extremities thereof extending outwardly in opposite directions, said lug being provided with alined keyway apertures, reinforcing means projecting through said apertures above 80 said outwardly extending extremities, the ends of the said lug being disposed substantially in alinement with said reinforcing means, and a body cast on said reinforcing means and the extremities of said lug.

WILLIAM M. SIMPSON.
